EX

OF D 12,368

Design No. 12,368, dated July 19, 1881.

UNITED STATES PATENT OFFICE.

DAVID S. PLUMB, OF NEW YORK, N. Y.

DESIGN FOR A MIRROR-FRAME.

SPECIFICATION forming part of Design No. 12,368, dated July 19, 1881.

Application filed May 28, 1881. Term of patent 3½ years.

To all whom it may concern:

Be it known that I, DAVID S. PLUMB, of the city, county, and State of New York, have invented a new and Improved Design for Mirror-Frames, of which the following is a full, clear, and exact specification.

In the accompanying photograph my newly-designed mirror-frame is shown by a front view.

The frame, as shown, is formed of an inner and an outer frame of bars, *a b*, between which is the open-work border, constituting the principal feature of the design. The open-work design between and connecting the bars *a b* is foliage in arabesque. At the bottom is a medallion, *c*, and there may be an ornamental figure at the top, as shown; but these are not essential.

This frame I produce in metal, and with this

design it has a light and handsome appearance.

Having thus described my invention, I claim as new and desire to secure by Design Patent—

1. The design for mirror-frame shown and described, consisting of a bordering of foliage in open-work arabesque.

2. The design for mirror-frames shown and described, consisting of arabesque foliage between and connecting the bars of an inner and an outer frame.

The above specification of my improved design for mirror-frames signed by me this 10th day of May, 1881.

DAVID S. PLUMB.
